UNITED STATES PATENT OFFICE.

JOHN FRANKLIN WHITMAN, OF ELKINS PARK, PENNSYLVANIA.

DESIGN FOR A MANTEL-CLOCK CASE.

42,448.

Specification for Design.

Patented Apr. 30, 1912.

Application filed February 17, 1911. Serial No. 609,268. Term of patent 14 years.

To all whom it may concern:

Be it known that I, JOHN FRANKLIN WHITMAN, a citizen of the United States, and a resident of Elkins Park, in the county of Montgomery and State of Pennsylvania, have invented a new, original, and ornamental Design for a Mantel-Clock Case, of which the following is a specification, reference being had to the accompanying drawings, forming part thereof.

Figure 1, shows an elevational view of a clock housing showing my new design, and Fig. 2, shows an end view thereof.

My design relates to a mantel clock case, the face of which includes a circular section having a dial opening surrounded by an egg-and-dart molding. The circular sec-

tion forms part of two triangular portions, each ending in a scroll, the face of each triangular portion being embellished by means of a flat fillet containing a spandrel ornament. The base of the case is ornamented by a water leaf molding extending around three sides of the case.

I claim:

The ornamental design for a mantel clock case as shown and described.

In testimony whereof I affix my signature, in presence of two witnesses.

JOHN FRANKLIN WHITMAN.

Witnesses:

A. TUHOLSKE,
T. MURRAY, Jr.
